CLAIM

The ornamental design for a wrist sleeve, as shown and described.

DESCRIPTION

FIG. 1 is a front perspective view of a wrist sleeve of the present invention showing my new design;

FIG. 2 is a front side elevation view thereof;

FIG. 3 is back side elevation view thereof;

FIG. 4 is a side elevation view thereof;

FIG. 5 is another side elevation view thereof

FIG. 6 is a top plan view thereof;

FIG. 7 is a bottom plan view thereof; and,

FIG. 8 is a perspective view of FIG. 1 in use.

In the drawings, the broken lines show portions of an elbow sleeve that forms no part of the claim; and depicts environment in FIG. 8 that form no part thereof.
